MAT DRIER

Andrew J. Hartley, Janesville, Wis.

Application January 16, 1933, Serial No. 652,066

3 Claims. (Cl. 34—16)

My invention relates to devices for drying mats used in casting stereotype printing plates, which are in a moist or semi-wet state. These mats are applied to the outer cylindrically curved exterior 5 surface or periphery of a hollow drying drum and an object of my invention is to effect the close conformation of the mat to the curved surface of the drum or support, and another object is to accomplish that by simple and efficient means 10 and to promote or facilitate the manipulations required to be performed, all as hereinafter more fully set forth in the description of that embodiment of my invention which I have selected for illustration thereof.

15 My invention consists in whatever is described by or is included within the terms or scope of the appended claims.

In the drawing:

Fig. 1 is a view in side elevation of enough of a 20 mat drier to illustrate an embodiment of my invention;

Fig. 2 is a detail view in perspective of a portion thereof with especial reference to the devices for 25 clamping the moist mat upon the periphery of the drying drum.

Briefly described, the embodiment of my invention shown in the drawing is a hollow drum with a curved exterior with two concentric asbestos blankets or sheets, the inner one of which 30 is in a fixed position and the outer is fixed at one end on a line parallel with the drum axis and at the other end is free and is engageable by a spring-actuated hook-form catch device which 35 draws and holds the outer one tightly upon the mat interposed between the two blankets, so that the mat is subjected to uniform pressure throughout its extent due to the force exerted by the spring in drawing or pulling the outer blanket upon the drum. The fixed end of the outer 40 blanket is attached to the periphery of a stationarily supported spring-actuated roller which tends to wind the outer blanket upon it so that when the latched or hooked end is released, the 45 blanket will automatically be wound upon such roller and thereby the dried mat released and at the same time the outer blanket will be conveniently taken care of ready for further use with another mat to be dried.

Describing in detail what is shown in the drawing, the hollow drying drum is designated 10, and the asbestos blanket fixed to the periphery thereof is designated 11, its opposite ends being suitably secured to the drum. Projecting from the drum, at opposite sides, are spaced apart bearings 13, for a rock shaft 14, which between its

ends has a hook-form arm 15, adapted to catch or latch into an eye or loop 16, fixed to the loose or free end of the outer asbestos blanket 17. Such free end is shown fixed between opposite metal strips, 12. The rock shaft has applied to it a coil spring 18, which tends to swing the hook upward and away from the free edge of the outer blanket so as to exert a drawing or pulling force upon it which causes the outer blanket snugly or closely to press the mat smoothly against the 10 inner blanket. The rock shaft has at one end a crank arm 19, by which to rock it against the action of the spring 18, to release the hook from the eye or loop and thus free the hitherto clamped mat.

The other end of the outer blanket, as has been explained, is secured to the periphery of a spring roller 20 (which may be similar to the familiar shade roller) which when the loose end of the outer blanket is freed from the pull of the hook arm, automatically rolls or winds the then loose outer blanket upon itself, freeing and exposing the mat for removal and exposing the inner blanket for the application of another mat.

To limit or stop the swing of the hook or latch 25 to unlatching position by the action of the spring on the rock shaft 14, a suitable stop may be provided such as a collar 21, fixed to the rock shaft and having a finger 22, situated to engage the side of the adjacent shaft bearing 13.

As will be evident from what I have already said, my invention may be embodied in constructions differing from that shown in the drawing and described in detail and the scope of my protection therefore, extends to and includes structures of various forms but embodying the same principle.

What I claim is:

1. A mat drier comprising a mat-supporting surface and a flexible mat-clamping member and releasable means exerting tension on such member between opposite edges thereof over a mat lying between it and such supporting surface, said means including a hook-form latch and an eye engageable therewith connected with one of the edges of said member a rock shaft journaled parallel with said edge and a spring acting on said rock shaft to cause the latch to exert pull on said eye.

2. A mat drier comprising a mat-supporting 50 surface and a flexible mat-clamping member and releasable means exerting tension on such member between opposite edges thereof over a mat lying between it and such supporting surface, and a stationarily supported winding roller to which 55

said member is connected and upon which it may be wound when it is free from such tension-exerting means.

3. A mat drier comprising a convexly curved, 5 mat-supporting surface, a flexible mat-clamping member secured along one side adjacent to said surface, and adapted to reach therefrom over such convexly-curved surface in contact with a mat

thereon and having its opposite edge free, when not in clamping position, and means for temporarily securing such free edge against the mat-supporting surface, such securing means including means to exert tension on said flexible member in a direction substantially tangential to such curved surface.

ANDREW J. HARTLEY.
